United States Patent Office.

BENJAMIN MONROE, OF BRISTOL, RHODE ISLAND, ASSIGNOR TO HIMSELF,
WILLIAM E. CHADWICK, AND NATHAN N. COLE, OF SAME PLACE.

Letters Patent No. 79,245, dated June 23, 1868.

IMPROVED CAR-COUPLING.

The Schedule referred to in these Letters Patent and making part of the same.

TO ALL WHOM IT MAY CONCERN:

Be it known that I, BENJAMIN MONROE, of Bristol, in the county of Bristol, and State of Rhode Island, have invented a new and useful Improvement in Car-Couplings; and I do hereby declare the following to be a full and correct description of the same, reference being had to the accompanying drawings, in which—

Figure 1 is a side view in perspective of my improved coupling.

Figure 2 is a longitudinal vertical central section of the same; and

Figure 3 is a top view of the link or shackle.

The same letter marks the same part wherever it occurs.

The object of this invention is to provide an automatic coupling, which will obviate the necessity of coupling by hand, a practice so fruitful in accidents to railroad-employees.

The nature of the invention consists in the use, in combination with a slotted draw-head, having a funnel-shaped orifice, of a draw-pin of peculiar construction, the two being so arranged as to receive and retain the head of a barbed link or shackle, all as hereinafter more fully set forth.

The form and construction of the various parts of the coupling are clearly illustrated in the drawings, whereon H marks the draw-heads, which, in general form, resemble those in common use. Their orifices are funnel-shaped, as shown in fig. 2, and they are provided with slots for the reception of the draw-pins B. The form of the pin B is shown in fig. 2. It is raised and lowered by the aid of the ring R.

The upper portion of the pin projects towards the orifice of the draw-head a greater distance than the lower portion, forming an arm, the under side of which is rounded in front, and provided with a shoulder, s, which, when the pin is in its lowest position, engages the barb of the link L.

The upper surface of the lower projection of the pin B is inclined downward, in a curve corresponding with that of the funnel-shaped orifice of the draw-head, so that when the pin B is raised till the two surfaces coincide, the arrow-head h of the link L can be withdrawn from the head H.

A pin, p, limits the upward movement of B, and a shoulder, a, resting upon a corresponding shoulder, b, in the head, limits its downward movement. The link or shackle L is provided with a head, h, the line of junction forming a shoulder or barb, by which the attachment of the link to the draw-head is effected.

The operation is as follows: As the head of the link enters the draw-head, it slides up the inclined surface and presses up the pin B, until it has passed within the catch or shoulder s, when the pin B falls, and engages with the upper barb of the link, the lower barb resting against a shoulder of the draw-head, as clearly shown in fig. 2. To release the link it is only necessary to raise the pin B until the surface on which the lower barb of head h rests is level with the interior incline of the draw-head, when the head h, being released both above and below, can readily be withdrawn.

Having thus fully described my invention, what I claim, and desire to secure by Letters Patent, is—

1. The combination of the draw-pin B, constructed as described, with the slotted draw-head H, having an inclined or funnel-shaped orifice, as described.

2. The combination of the head H, pin B, and link L, all constructed and operating as and for the purpose specified.

The above specification of my said invention signed and witnessed at Bristol, this 25th day of February, A. D. 1868.

BENJAMIN MONROE.
